(57) **CLAIM**

The ornamental design for a replacement headband cushion kit, as shown and described.

DESCRIPTION

FIG. 1 is a first perspective view of a replacement headband cushion kit showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the replacement headband cushion kit thereof; and,

FIG. 10 is an exploded view of the replacement headband cushion kit thereof.

The broken lines shown in the drawings depict portions of the replacement headband cushion kit that form no part of the claimed design.

1 Claim, 10 Drawing Sheets
